FIG. 1.

FIG. 2.

FIG. 3.

FIG. 4.

FIG. 1 is a side elevational view of a first embodiment of the combination fish line stabilizer and sinker showing my new design, the opposite or back side is a flat surface;

FIG. 2 is a plan view of the stabilizer and sinker shown in FIG. 1 and which indicates that the back side is planar;

FIG. 3 is a side elevational view of a second embodiment of the invention in which the back side is identical but opposite hand; and

FIG. 4 is a plan view of the embodiment shown in FIG. 3.

The present application is a continuation in part of my present application Ser. No. D. 23,357, filed June 8, 1970, now abandoned.

I claim:

The ornamental design for a combination fish line stabilizer and sinker, substantially as shown and described.
